UNITED STATES PATENT OFFICE.

GEORGE H. SMITH, OF FOREST HILL, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

No. 866,606.

Specification of Letters Patent.

Patented Sept. 17, 1907.

Original application filed August 27, 1900, Serial No. 28,142. Divided and this application filed January 26, 1906.
Serial No. 297,962.

To all whom it may concern:

Be it known that I, GEORGE H. SMITH, a citizen of the United States, and a resident of Forest Hill, in the county of Essex and State of New Jersey, have invented 5 certain new and useful Improvements in Type-Writing Machines, of which the following is a specification.

My invention relates to typewriting machines and has for its object to provide an improved platen shift for such machines.

10 My invention consists in certain features of construction and combinations and arrangements of parts, all of which will be hereinafter described and particularly pointed out in the claims.

This application is a division of my application for 15 Letters Patent for typewriters, Serial No. 28,142, filed August 27, 1900.

In the accompanying drawings, Figure 1 is a fragmentary top plan view of as much of a typewriting machine as is necessary to illustrate my invention. Fig. 2 20 is a front elevation of the machine with parts omitted. Fig. 3 is a vertical section substantially on the line x—x of Fig. 2 and looking toward the left. Fig. 4 is a view in perspective of a detail of the shifting mechanism.

In the drawings, A designates the main frame, which 25 has a top plate A'. From said top plate rise suitable posts A² and A³, which support the rear guide rail A⁴ and the front guide rail A⁵ respectively, on which guide rails the carriage moves from side to side in the usual way. In such motion the carriage may be actuated by 30 the usual spring mechanism and controlled by the usual or any suitable escapement mechanism; but as these parts are well known and form no part of the present invention, they have not been shown herein.

The carriage comprises a substantially rectangular 35 frame B provided with a pair of traverse rollers B² to run on the back rail A⁴, and a single front roller B² to run on the front rail A⁵. In the side bars of the carriage frame are depressions B⁷ to allow for the vertical movement of the shaft D' of the platen D as the same is shifted 40 for upper and lower case printing. The shaft D' of the platen is mounted in bearings formed in a platen frame E, having longitudinal connecting bars E' at the rear (Fig. 1) and E' at the bottom (Fig. 2). This platen frame is pivotally connected, at the lower portion thereof to 45 crank arms F' as indicated at F', said crank arms being secured to a rock shaft F² journaled in the carriage, whereas the upper portion of said platen frame is pivoted at each side, as indicated at F', to one end of a link F, the opposite end of which is pivoted at B' to 50 the carriage. The links F and crank arms F' constitute in effect, parallel links on which the platen frame and platen receive vertical movements to change the printing position. The shifting mechanism comprises

a rock shaft G² pivoted in lugs G²⁰ rising from the top plate A' of the machine. Arms G, projecting from the 55 rock shaft G², are connected at their outer ends to a supporting or shift rail G' which supports a roller E³ mounted in the lower longitudinal bar E² of the platen frame. A bracket E¹⁰, depending from said bar E², has a lug or rearwardly bent end E¹¹ projecting beneath the 60 rail G' to prevent the roller E³ from being raised off of the rail G' by violent shifting of the platen or in any other manner.

The rock shaft G² has connected to one end thereof, a crank arm G² which is connected by a link G³ with an arm G⁴ that projects from one end of a rock shaft G⁶ that is pivoted in lugs G⁷ rising from a portion of the main frame A at the front thereof. This rock shaft G⁶ has secured thereto at its opposite end, a hand operated actuating arm G⁵ provided with a shift key G¹⁵ at the key-board of the machine (see Fig. 2). It will be seen that if the shift key G¹⁵ be depressed, the platen frame and platen will be elevated, and on the release of the key, the platen and platen frame will move to their normal positions by their own weight. 75

The weight of the platen and platen frame is partially taken up by coiled springs F³ which surround the rock shaft F². Each of the springs F³ is connected at one end to a collar F¹⁰ on the shaft F² and at the other end to a bracket F¹¹ projecting from the carriage frame and encircling the shaft F². Each of the crank arms F' is fixed on the shaft F² between the carriage and the encircling portion of one of the brackets F¹¹. The upward movement of the rail G' is limited by an arm G¹⁰, which projects downwardly and then forwardly from one of the center crank arms G, abutting against an adjusting screw G¹¹; whereas the downward movement of the platen and its frame is limited by adjustable screws E⁴ threaded through lugs B¹⁴ projecting from the carriage frame B, and with which forwardly projecting 80 arms E⁸ on the platen frame coöperate. 85

I have provided means whereby the platen frame may be held in its upper case position if desired. An arm G⁹ projects upwardly from the shaft G⁶ to which it is fixedly secured. In the present instance the arm G⁹ 90 is formed as a part of the crank arm G⁶. Near the upper end of the arm G⁹ a three-armed lever H is pivoted at H² to a lug H¹⁰ projecting from one of the frame posts A¹⁰ which support the top plate A'. One arm H' of the lever H has a lug H² projecting therefrom in position to 100 engage the crank arm G⁹. Another and upwardly directed arm H³ of said lever has projecting therefrom a lug H⁴ which is connected by a spring H⁵ to a stud H⁶ projecting from the frame post A¹⁰. The third arm of the three-armed lever projects forwardly and is in position to be conveniently manipulated. When the parts 105

are in their normal positions, shown in Figs. 3 and 4, the spring H^6 holds the lever arm H against a fixed stop H^{11} , projecting from the frame post A^{10} ; but the construction is such that if the forwardly projecting arm of the lever 5 be raised until the stud H^4 passes the dead center or the pivotal center H^8 of the three-armed lever, then the spring H^6 will press the lug H^2 against the crank arm G^9 and press said crank arm towards the front of the machine, thus moving the platen frame to upper case position 10 and holding it in such position. It will be seen that the spring H^6 is adapted to hold the three-armed lever H in either of the two positions which it is adapted to occupy.

What I claim as new and desire to secure by Letters 15 Patent is:—

1. In a front-strike typewriting machine, the combination of a carriage, a vertically movable platen frame carrying a platen, a vertically movable shift-rail located beneath the platen, means for effecting a vertical movement 20 of said shift-rail, a rock-shaft carried by said carriage, crank arms carried by the rock-shaft and connected to said platen frame, a counter-balancing spring connected to the rock-shaft, and links connected to the platen frame and to the carriage and which with the crank arms constitute in effect parallel links on which the platen frame 25 moves during the vertical shift thereof.

2. In a typewriting machine, the combination of a platen, means for shifting said platen in a direction transverse to the length thereof for upper and lower case writing, a spring-pressed stop that is shiftable to two positions and is adapted to be maintained by its spring in either of the two positions to which it may be moved and which is independent of the said shifting means, the relation between the stop and the shifting means being such that in 35 one position of the stop it will coöperate with the shifting means to retain the platen in the shifted position, whereas in the other position the said stop is carried out of co-operative relation with the shifting means.

3. In a front-strike typewriting machine, the combination of a carriage, a vertically movable shift rail located beneath the platen and which supports and shifts the platen of said carriage vertically, shifting means operatively connected to the shift rail, and a spring-pressed hand operated pivoted lever shiftable to two positions and 40 which when in one position, coöperates with the shifting means to maintain the platen in a shifted position, but when in the other position does not affect said shifting means, the spring of said lever being effective to exert a force upon one or the other side of the pivotal center of 45 said lever according as said lever is in one or the other of its positions.

4. In a front-strike typewriting machine, the combination of a carriage, a vertically movable shift rail which shifts the platen of said carriage vertically, shifting means operatively connected to the shift rail and spring 55 pressed hand operated lever shiftable to two positions and which coöperates with the shifting means when said lever is in one position to maintain the platen in a shifted position and is out of co-operative relation with said shifting means when the lever is in another position, the spring of said lever being effective to exert a force upon one or the other side of the pivotal center of said lever.

5. In a front-strike typewriting machine, the combination of a carriage, a hand-operated spring pressed lever pivoted to a fixed portion of the machine and which constitutes a stop to maintain the platen in the shifted position, the spring of which lever is adapted to exert its force upon one or the other side of the pivot of said lever in accordance with the position of the lever, a vertically movable shift rail upon which the platen is supported, and intermediate operative connections between said shift rail and said lever.

6. In a front-strike typewriting machine, the combination of a carriage, a hand operated spring pressed pivoted lever, the spring of which is adapted to exert its force upon one or the other side of the pivot of the lever in accordance with the position of said lever, a vertically movable shift rail upon which the platen is supported, intermediate operative connections between said shift rail and said lever for moving and maintaining the platen in the shifted position, and a shift key operatively connected to the shift rail and independent of said lever for temporarily shifting the platen and permitting it to resume its normal position when pressure upon said shift key has been released.

7. In a front-strike writing machine, the combination of a carriage, a hand-operated spring pressed pivoted lever, the spring of which is adapted to exert its force upon one or the other side of the pivot of said lever in accordance with the position of said lever, a vertically movable shift rail upon which the platen is supported, a rock shaft which is operatively connected to said shift rail, an arm extending from said shaft and which is disconnected from but is adapted to coöperate with said lever, and a finger key for operating said rock shaft, whereby the rail and platen may be shifted and maintained in the shifted position by the said lever or may be temporarily shifted by the finger key and allowed to assume the normal position when pressure is released from said key.

8. The combination of a shiftable platen, a case-shift key for moving said platen to shifted position, and spring means normally out of operative connection with said platen but adapted to be brought into operation to move said platen to shifted position.

9. The combination of a shiftable platen normally held by gravity in lower case position, a key for moving said platen to upper case position, and spring means normally out of operative connection with said platen but adapted to be brought into operation to move said platen to upper case position, and to hold said platen in such position.

10. In a typewriting machine, the combination of a shifting platen, a shift rail therefor, a key actuated rock-shaft for moving said shift rail, a crank-arm extending from said rock-shaft, a three-arm pivoted lever, one arm of said lever being disconnected from but adapted in one position of the lever to coöperate with said crank arm and to be moved out of coöperation with said crank arm in another position of said lever, another arm of said lever carrying a finger piece for moving the lever, and a spring connected to the third arm of said lever and adapted to be shifted to either side of the pivotal center of said lever.

Signed at the borough of Manhattan, city of New York, in the county of New York, and State of New York, this 25th day of January, A. D. 1906.

GEORGE H. SMITH.
